UNITED STATES PATENT OFFICE.

CHARLES FRANCIS JENKINS, OF WASHINGTON, DISTRICT OF COLUMBIA.

COOLING DEVICE FOR MOTION-PICTURE MACHINES.

1,408,203.

Specification of Letters Patent. Patented Feb. 28, 1922.

Application filed May 19, 1919. Serial No. 298,265.

To all whom it may concern:

Be it known that I, CHARLES FRANCIS JENKINS, a citizen of the United States, and resident of Washington, in the District of Columbia, have invented certain new and useful Improvements in Cooling Devices for Motion-Picture Machines, of which the following is a specification, reference being had therein to the accompanying drawing.

- 10 In motion picture exhibiting, safeguarding against fire is of enough importance to warrant employing entirely distinct expedients in the same machine so that assurance of safety may be doubly sure under any and all possible conditions. Many expedients have been devised some limiting combustion to a single picture, some reducing the temperature of the light beam, some running in open air a shutter between the lamp and film, 15 some in one way or another limiting combustion to the short length of film at any one time outside fireproof reel chambers, some cutting off light whenever the film stops or is reduced in speed.
- 20 This invention employs, either alone or in connection with one or more of other devices for similar purposes, a cool air blast over the film at the exposure point, the air being normal atmosphere, chilled air, or highly compressed air allowed to expand just before it reaches the film and so reduced in temperature.

In the accompanying drawings,

Figure 1 is a vertical section looking 35 toward the edge of the film at the exposure opening.

Figure 2 is a section on the line 2—2 of Fig. 1.

As shown, A represents a plate having an exposure opening at B, C a film passed 40 across the opening in any suitable way, D

a chamber holding air under any desired tension, E an expansion chamber discharging, by a passage F, across the face of the film, and G a valved conduit leading from the reservoir D to the chamber E where the air is allowed to expand, if it be under material compression.

When the machine is in operation the valve is opened so as to allow the desired 50 stream of air to pass into the chamber E and thence upwardly over the face of the film and across the path of the light beam advancing in the direction of the arrow x. The air readily escapes from the usual casting or box, but the box is not necessarily 55 without special air exits.

What I claim is:

1. In a motion picture projecting machine, the combination with a fixed plate having 60 an exposure opening, of means for feeding picture film along one face of the plate and across said opening, of an air-expansion chamber discharging across said opening through a transversely narrow elongated 65 slot, and means for supplying materially compressed air in said chamber, whereby air cold through expansion may pass in an even thin stratum across the path of light to the film.

2. The combination with a plate having the usual light opening across which motion picture film is fed in projecting, of an air expansion chamber at the face of the plate alongside said opening and closed except for 75 a narrow slot adapted to discharge a broad thin film of air across the opening, and valve controlled means for discharging compressed air in said chamber.

In testimony whereof I hereunto affix my 80 signature.

CHARLES FRANCIS JENKINS.
